fumerie De Luxe, Paris, France

Application July 14, 1945, Serial No. 120,698
In France January 25, 1944

Term of patent 14 years

(Cl. D58—8)

To all whom it may concern:

Be it known that I, Amédée d'Anselme, a citizen of France, residing at Paris, France, have invented a new, original, and ornamental Design for Flasks, of which the following is a specification, reference being had to the accompanying drawing, forming part thereof.

The figure is a side elevational view of a flask showing my design.

The flask is circular in horizontal section throughout its height.

I claim:

The ornamental design for a flask, as shown and described.

AMÉDÉE D'ANSELME.
